RADIATOR COVER OR SHIELD

Kenneth E. Crooks, Williamsport, Pa.

Application May 14, 1935, Serial No. 21,433

3 Claims. (Cl. 237—79)

This invention relates to certain new and useful improvements in radiator covers or shields, the object being to provide a cover which can be manufactured very cheaply and one which when in place will not retard the heated air currents to any great extent, thereby overcoming the difficulties existing with impervious radiator covers now in use as I have found in practice that with an impervious radiator cover it is necessary to maintain the radiator at a greater temperature in order to heat the room in which it is disposed.

Another object of my invention is to provide a radiator cover which will filter the air currents arising adjacent the radiator to prevent the discoloring of the walls of the room by the depositing thereon of dirt and dust carried by the air currents caused by the heat of the radiator.

Other and further objects and advantages of the invention will be hereinafter set forth and the novel features thereof defined by the appended claims.

In the drawing,

Figure 1 is an end view of one form of cover showing the back and top portion formed of pervious material and the front portion formed of open mesh, the cover extending from the floor at the back of the radiator to the floor in front of the radiator; and

Figure 2 is an end view of a modified form of cover showing the back portion formed of non-pervious material, the top portion formed of pervious material and the front portion formed of open mesh material.

It will also be apparent that if desired the cover could be formed of such a length that it could drop down in front of the radiator to completely enclose the front or could be dropped down to any desired distance and therefore I do not wish to limit myself to the forming of a pervious cover of any particular length or width.

In some instances I preferably treat the cloth from which the cover is made with a dust collecting agent to more thoroughly collect the dust rising in the currents of air and I wish it to be clearly understood that I do not wish to limit myself to the texture of the material or the way it is treated so long as the material from which the cover or shield is formed is held in position on the radiator by frictional contact therewith.

By constructing a radiator cover or shield so as to thoroughly protect or enclose the radiator of fabric, the fabric can be made of material to correspond to the paper on the walls of the room

in which it is used or can be made to correspond with the walls and trim so that there is a perfect blend between the cover and the room in which it is disposed and therefore I do not wish to limit myself to the use of any particular manner of forming the cover or shield or the particular material from which it is formed so long as a portion of the same is pervious in order to allow the ascending air currents to pass therethrough so that the dust and dirt will be filtered from the ascending air currents in order to prevent the discoloring of the walls and ceiling of the room in which the radiator is disposed.

While I prefer to use a cloth formed of wool, silk, cotton or the like, any kind of foraminous material, such as pervious paper, metal cloth can be used to form the cover so long as it allows the ascending air currents to pass therethrough and yet will filter the air to prevent the discoloring of the ceiling and walls of the room in which the radiator is disposed.

It will, of course, be understood that my invention consists broadly in providing a cover or shield of material which will prevent the discoloring of the walls and ceiling and therefore I reserve the right to form the cover of any kind of material desired, such as paper, cloth, or analogous material which will perform the function desired.

In the construction of radiator disclosed in Figure 1, the back and top portion A of the cover is formed of pervious material and the front B is formed of open mesh material and the cover is of such a length that it reaches from the floor back of the radiator to the floor at the front of the radiator and is held thereon by frictional contact. This provides a construction for completely covering the radiator with the exception of the ends and by having the front of open mesh, the air is not retarded to any extent so as to allow it to pass freely into the radiator and as it rises foreign matter is collected so as to prevent the wall from being discolored. The open mesh can be formed of any kind of material desired so long as it allows a free circulation of air.

In the modification shown in Figure 2, the cover is provided with a non-pervious back portion C, pervious top D and an open mesh front portion E, the cover extending from the floor at the back of the radiator to the floor at the front of the radiator so as to completely enclose the radiator with the exception of the ends and this provides means for reflecting the heat and yet protects the radiator.

While in the drawing I have illustrated a cover extending from the top of the radiator to the floor, it is, of course, understood that the cover could terminate short of the floor without departing from the spirit of my invention as defined in the appended claims.

What I claim is:

- 5 1. A radiator cover formed of foraminous flexible material having the rear portion thereof formed of non-pervious material extending from the top of the radiator to the bottom thereof and the front portion extending from the top downwardly therefrom, the portion in the front of the radiator being of open mesh material in order to 10 allow air to pass into the radiator and the portion from the top of the radiator forming the material to filter the air in its passage there-
- 15

through in order to prevent the discoloring of the walls and ceiling in the room in which the radiator is disposed.

2. A radiator cover formed of flexible material having a non-pervious rear portion and a front and top portion formed of pervious material, said cover being held in position thereon by frictional contact with the radiator.

3. A radiator cover formed of flexible material having a non-pervious rear portion, a top portion of pervious material and a front portion of open mesh material, said cover extending from the floor in the back of the radiator to the floor in front of the radiator, and held in position thereon by frictional contact with said radiator. 10 15
